(57) **CLAIM**

The ornamental design for a cordless telephone handset, as shown and described.

DESCRIPTION

FIG. 1 is a front perspective view of the cordless telephone handset of the present invention, sitting in a cordless telephone handset cradle shown in dotted lines;

FIG. 2 is a front perspective view of the cordless telephone handset of the present invention, reclined on a cordless telephone handset base station shown in dotted lines;

FIG. 3 is a front elevation view of the cordless telephone handset; and,

FIG. 4 is a rear elevation view of the cordless telephone handset.

The broken line showings of a cradle in FIG. 1 and of a base station in FIG. 2 are for illustrative purposes only and form no part of the claimed design.

1 Claim, 4 Drawing Sheets

FIG. 1

FIG. 2

FIG. 3

FIG. 4
